UNITED STATES PATENT OFFICE

135,904

DESIGN FOR A TAILSTOCK FOR LATHES

William M. McConnell, McKeesport, Pa., assignor
to Mackintosh-Hemphill Company, Pittsburgh,
Pa., a corporation of Delaware

Application August 21, 1942, Serial No. 107,985

Term of patent 14 years

To all whom it may concern:

Be it known that I, William M. McConnell, a citizen of the United States, residing in McKeesport, in the county of Allegheny and State of Pennsylvania, have invented a new, original, and ornamental Design for a Tailstock for Lathes, of which the following is a specification, reference being had to the accompanying drawing forming a part thereof.

In the drawing:

Fig. I is a perspective view of a tailstock for lathes showing my new design, the said tailstock being viewed from the rear and to one side thereof.

Fig. II is an elevational view of the side opposite that shown in Fig. I.

I claim:

The ornamental design for a tailstock for lathes, substantially as shown.

WILLIAM M. McCONNELL,
